UNITED STATES PATENT OFFICE.

GEORGE L. BABB AND CLYDE P. WAGNER, OF JOPLIN, MISSOURI.

GOLF-TEE MOLD.

Application filed August 9, 1924. Serial No. 731,126.

To all whom it may concern:

Be it known that we, GEORGE L. BABB and CLYDE P. WAGNER, citizens of the United States, residing at Joplin, in the county of

- 5 Jasper and State of Missouri, have invented certain new and useful Improvements in Golf-Tee Molds, of which the following is a specification, reference being had to the accompanying drawings.
- 10 This invention relates to golf tee molds and has for an important object thereof the provision of a device of this character forming a well compacted tee in the single motion of engaging the mold in the sand of the
- 15 sand box.

A further object of the invention is to provide a device of this character which may be extremely cheaply produced and in which the ejection of the completed tee is automatic.

20 These and other objects we attain by the construction shown in the accompanying drawings, wherein for the purpose of illustration is shown a preferred embodiment of our invention and wherein:—

25 Figure 1 is a side elevation of a tee mold constructed in accordance with our invention, showing the same prior to engagement in the sand of the sand box;

30 Figure 2 is a similar view showing the same after engagement in the sand box;

Figure 3 is a vertical sectional view through the tee mold;

35 Figure 4 is a perspective view thereof. Referring now more particularly to the drawings, the numeral 10 indicates similar curved side walls combining to form a frusto-conical mold having an open top and bottom. Secured to the sections are the ends

40 of an inverted U-shaped spring 11, which by its resiliency normally maintains the edges 12 of the sections in spaced relation to one another. Secured to the bight portion of the spring 11 is a tube 13 through which and

45 through an opening 14 formed in the bight of the spring is directed a shaft 15 having at its upper end a button head 16 and at its lower end a plunger head 17. Within the sleeve a spring 18 surrounds the shaft abutting the spring 11 at its upper end and the plunger head at its lower end.

50 In the use of the device, the sections 10 are forced into the sand until the sand has filled the space between the sections and the plunger head has been forced upwardly. The sections 10 are then forced toward one

another, pressing the sand between their adjacent faces and engaging the plunger so as to prevent its downward movement under the influence of the spring. The device is 60 then lifted from the sand box and placed upon the ground at the desired point, after which the grip upon the sections 10 is released and the plunger forces the molded tee out upon the ground where it is ready for use 65 as a ball support. A tee mold of this character uses but a small quantity of sand, just sufficient for the formation of the tee, and due to its construction provides a uniform tee which, as well known to those familiar 70 with the game of golf, is necessary for accuracy in driving.

75 Since the device is capable of a certain range of change and modification without materially departing from the spirit of our invention, we do not limit ourselves to such specific structure as hereinbefore set forth except as hereinafter claimed.

We claim:—

1. In a tee mold, a plurality of curved 80 side wall sections combining to form a frusto-conical mold having an open top and bottom, a spring connecting the sections and normally holding them with their side edges in slightly spaced relation, and a top 85 for the mold supported from the spring and limiting movement of the sections toward one another when the spring is compressed.

2. In a tee mold, a plurality of curved 90 side wall sections combining to form a frusto-conical mold having an open top and bottom, a spring connecting the sections and normally holding them with their side edges in slightly spaced relation, and a top for the mold supported from the spring and 95 limiting movement of the sections toward one another when the spring is compressed, said top being normally yieldably held at a point spaced below the upper end of the mold and between the sections and being forced upwardly by engagement with the material to be molded as the mold is forced 100 therein.

3. In a tee mold, a plurality of curved 105 side wall sections combining to form a frusto-conical mold having an open top and bottom, a spring connecting the sections and normally holding them with their side edges in slightly spaced relation, and a top for the mold supported from the spring and 110 limiting movement of the sections toward one another when the spring is compressed,

- a tube secured to the spring and extending downwardly toward the upper end of the mold, the spring having an opening axial with the bore of the tube, a shaft for the top extended through the tube and opening of the spring and having a head at its upper end limiting downward movement of the top with the top spaced slightly below the upper end of the mold.
- 10 4. In a tee mold, a plurality of curved side wall sections combining to form a frustro-conical mold having an open top and bottom, a spring connecting the sections and normally holding them with their side edges in slightly spaced relation, a top for the mold supported from the spring and limiting movement of the sections toward

one another when the spring is compressed, a tube secured to the spring and extending downwardly toward the upper end of the mold, the spring having an opening axial with the bore of the tube, a shaft for the top extended through the tube and opening of the spring and having a head at its upper end limiting downward movement of the top with the top spaced slightly below the upper end of the mold, and a spring surrounding the shaft within the tube and abutting the cover to normally urge the same downwardly.

25 30 In testimony whereof we hereunto affix our signatures.

GEORGE L. BABB.
CLYDE P. WAGNER.
